METHOD OF DISTILLING PETROLEUM

Filed June 18, 1923

FIG. 1.

FIG. 2

FIG. 3.

Inventor

Henry H. Hewetson
By D. G. Messenger
Attorney

UNITED STATES PATENT OFFICE.

HENRY H. HEWETSON, OF ELIZABETH, NEW JERSEY, ASSIGNOR TO STANDARD OIL DEVELOPMENT COMPANY, A CORPORATION OF DELAWARE.

METHOD OF DISTILLING PETROLEUM.

Application filed June 18, 1923. Serial No. 646,005.

This invention relates to the art of distilling hydrocarbons and will be fully understood from the following description, taken in connection with the accompanying drawing in which—

5 Fig. 1 is a side elevation of one form of apparatus embodying my invention;

Fig. 2 is a plan view of the same; and

10 Fig. 3 is a detail, showing on an enlarged scale one form of construction for the fluid lift.

As shown in the drawing, the reference character 1 designates a still heated by any means, as desired, and having a vapor pipe 2 (shown partly broken away for clearness) leading to a fractional condenser tower 3. From the condenser tower 3 a vapor pipe 4 proceeds to a condenser coil in the water-containing condenser box 5. Another still 10 is mounted alongside the first still and similarly has a vapor pipe 12 and fractional condenser 13; and additional stills may be provided, all in series to any number desired. From the lower part of still 1 a pipe 6 connects to discharge into the tower 13 of the next still. Preferably this connecting pipe extends down below the level of the still and thence has a riser section leading to the point of discharge; and projecting into the riser section is a pipe 7 for admission of a fluid, for example steam, by means of which discharge is effected. The precise construction of the fluid inlet may vary. A simple form comprises an internal pipe extension 8 sealed leak-tight with the wall of the discharge pipe at point of entry and having a plurality of orifices 9.

In operation, oil being fed into the still 1 from a suitable source, vapors will be taken off for the temperature prevailing in the still and will pass over to the fractional condenser 3 where heavier constituents are condensed out and may be returned to the still by the reflux pipe R, while the desired constituents pass on by pipe 4 to the final condenser. At the same time the unvaporized residue in the still is forwarded by the steam lift 8 and discharged into the tower 13 of the next still, so

as to flow down therein counter-currently to the rising vapors, and then proceeds through the reflux pipe for that tower down to feed the still 10. The steam introduced into the connecting or discharge pipe from the still not only enables transfer of the oil from the still but also assists in the distillation.

55 While my invention is particularly advantageous with stills in a series or battery where the fluid lift moves the unvaporized residue from one still to the tower of the next still and so on through the series, I also contemplate in some cases connecting the fluid lift discharge line from one still directly to the next, or from a still directly into its own tower; and generally in distillation or vapor separating apparatus I contemplate connecting a fluid lift line to pick up liquid oil whenever it may be left, whether to move it from a still or even from the bottom of a fractional condensing tower and raise it up to discharge into the same tower.

60 Instead of a simply perforated steam inlet pipe, if desired the inlet may take other forms, such for instance as a jet, or an ejector form, and while steam is preferred for the operation of the lift, other convenient fluids 65 may be used; and the advantages of my invention may be realized correspondingly by even injecting water, in which case steam generation in situ results.

70 What I claim is:

80 The method of continuously distilling petroleum which comprises maintaining a series of bodies of petroleum at successively higher temperatures, conducting away and condensing the vapors so formed, maintaining a continuously flowing stream of petroleum from each body to that at the next higher temperature, each stream having a down-flowing and up-flowing section, introducing into said stream a quantity of a liquid having a boiling point lower than the temperature of the stream, to produce by vaporization a gas or vapor in the form of bubbles commingled with the liquid in the up-flowing section.

85 90 95 HENRY H. HEWETSON.
